UNITED STATES PATENT OFFICE.

ORREN A. SAWYER AND MOSES M. LAHUE, OF LOWELL, MASSACHUSETTS.

SHUTTLE CHECKING AND RELEASING MECHANISM FOR LOOMS.

SPECIFICATION forming part of Letters Patent No. 430,694, dated June 24, 1890.

Application filed September 18, 1886. Serial No. 213,937. (No model.)

To all whom it may concern:

Be it known that we, ORREN A. SAWYER and MOSES M. LAHUE, of Lowell, in the county of Middlesex and State of Massachusetts, have invented a new and useful Improvement 5 in Shuttle Checking and Releasing Mechanisms for Looms, of which the following is a specification.

Our invention relates to looms for weaving; 10 and it consists in certain new and useful constructions and combinations of the several parts thereof, substantially as hereinafter described and claimed.

In the drawings, Figure 1 is an end elevation 15 of a portion of the frame and mechanism of a loom, showing our improvement. Fig. 2 is a portion of a front elevation of the same, with the cloth roll or beam removed and breast-beam broken away to show the construction of the parts relating to our invention more clearly. Fig. 3 is an enlarged perspective view of a portion of the lay-beam, showing the shuttle-box and shuttle therein and a portion of the picker-staff with the attached parts of our improvement applied. Fig. 25 4 is a side elevation of a portion of the loom-frame shown in Fig. 1, provided with a modified form of our improvement. Fig. 5 is a detail view showing a modification of the 30 yielding cam shown in Fig. 6, as hereinafter described. Fig. 6 is an end elevation of a portion of the loom-frame and parts shown in Fig. 1, with a modified form of our improvement attached thereto. Fig. 7 is a front elevation of Fig. 6.

Our improvement consists of a lever and cam mechanism attached to the lay and frame of the loom, operating to give the shuttle-binder a compression at the moment the shuttle is received in the shuttle-box, and to release it at the moment that the shuttle is thrown from the box, substantially as herein-after described and claimed.

A is the frame of the loom.

45 B is the lay-beam, mounted upon arms b b , which are mounted at their lower ends on the reciprocating revolving rod b' . The lay-beam is vibrated back and forth to beat up the weft by the ordinary cam mechanism connected to 50 the links b^2 , attached to the arms b b on each side, as shown in Fig. 1.

S are the shuttle-boxes, mounted on each

end of the lay-beam in the ordinary manner.

P are the picker-staffs, vibrating back and forth in slots through the lay-beam and in the 55 shuttle-boxes to throw the shuttle through the shed in the usual way. They are pivoted to the rod b' .

The shuttle-binder s forms one side of each shuttle-box, being pivoted at s' by a vertical 60 pivot in the usual manner, and capable of being moved inward toward the opposite side of the box to narrow the space which receives the shuttle or swung outward to widen it.

B' is the breast-beam of the loom, and B² is 65 the roller on which the cloth is wound.

All of these parts are old and in common use, and will be readily understood without further description.

To one side of each shuttle-box we attach 70 a bent arm c' , which, curving upward and over the shuttle-box above the path of the shuttle, carries pivoted to its outer end the dependent lever c' , which hangs down past the shuttle-binder on the opposite side of the shuttle-box, and has upon it a projection in the form of a finger c^2 , which bears against the outer face of the binder, as shown in Figs. 1, 2, and 3.

To the side of the frame A we attach a 80 bracket or ear d , and upon this we attach the elastic rod or arm d' , carrying on its upper surface the cam-shaped enlargement or projection d^2 , underneath the path of the lower end of lever c' . The screw which is used to 85 secure the arm d' and cam d^2 to the stud d passes downward through a hole in the strip elongated longitudinally thereof, so as to allow the cam to be set or adjusted at different points beneath the lay, as desired, before the 90 screw is set up. The lower end of the dependent lever c' is provided with a roller c^3 , pivoted in a bifurcation therein, so as to roll across the face of cam d^2 to prevent undue friction; but this roller can be dispensed with 95 and the lower end of the lever made to bear directly upon the cam, if desired, especially when a heavy shuttle is used on a broad loom. The cam d^2 is shown as so placed that the lower end of lever c' will impinge against it 100 on the side nearest the breast-beam during the last part of the movement of the lay in one direction—*i. e.*, from the breast-beam—thus releasing the shuttle-binder from com-

pression; but this is the moment when the shuttle is thrown by the picker-staff, and the shuttle therefore leaves the shuttle-box freely. During the first part of the return movement of the lay in the other direction—*i. e.*, toward the breast-beam—the lower end of lever c' impinges upon the opposite side of cam d^2 and presses the finger c^2 against the binder s ; but this is the moment when the shuttle is received in the shuttle-box as it is thrown through the shed, and the force of the shuttle is therefore checked by the compression of the binder, which expands outward harder and harder as the shuttle forces its way into the box, because it moves the lower end of lever c' upon the higher part of cam d^2 as it expands. This nipping of the shuttle by the binder should, as above stated, occur at the moment when the shuttle is received into the shuttle-box, and while it is passing through the same. The binder in this action does not tend to prevent the shuttle entering the box, but arrests it after it has entered and while it is moving through the same, thus acting the same on shuttles thrown with varying force. By varying the inclination of cam d^2 and the stiffness of its elastic arm d' any desired increase of this nipping tension may be had which is desired. The continued movement of the lay toward the breast-beam also contributes to increase the pressure upon or nip the shuttle in its box, thus applying it by degrees, so to speak, and preventing breakages by too sudden stoppage of the shuttle. It is not necessary that the spring which allows of the yielding pressure on the shuttle-binder should be attached to the cam, but it may be located so as to allow some part of the mechanism between the cam and the binder to have the necessary elasticity, as illustrated by Fig. 4. For instance, as shown in Fig. 4, the cam d^2 may be fixed directly to the frame by bolts and slots, as shown, and the lever c' may be made thin and elastic, as shown, so as to yield and allow it to pass over the cam, or with the cam so made non-elastic the mechanism shown in Fig. 3 may be employed, with the arm c^2 made of elastic material to allow of such yielding to the cam and create a spring-pressure upon the binder. The cam shown in Fig. 4 may also be used in place of that shown in Fig. 1, if desired, and the shuttle be nipped by a positive movement, increasing in intensity with the progress of the lever c' over the cam, as before described. The position of the opposite faces of the cam d^2 in alternately withdrawing and applying the pressure of the finger c^2 to the shuttle-binder momentarily during the backward and return stroke of the lay-beam is of importance, because this construction of the parts avoids friction and enables the lay to move with great speed and the weaving to proceed faster, as the lay makes almost or quite a half-beat to and fro while the shuttle passes across from one box to the other, and is properly released and nipped in the box,

as described, after it has entered the same. This construction also allows the arm c' and finger c^2 to press lightly against the shuttle-binder s at all times, except when the same is momentarily withdrawn from or forced against the binder by the motion of the cam, and this prevents the shuttle from flying out of its box, while permitting it to be removed and replaced by hand therein at every other part of the movement of the lay at which the loom may happen to be stopped. It will also be observed that the shuttle-binder is formed curved on its inner face, so as to wedge against the entire side of the shuttle and present increasing resistance, with a large bearing-surface upon the shuttle as it advances farther into the box.

In these details of construction, arrangement, and operation this mechanism differs from the ordinary protection-rod mechanism, which is constructed to bear upon the shuttle or the side of the shuttle-box after the shuttle is lodged in the same, and by continuously bearing thereon during the beat-up of the lay, hold the dagger out of the way of its stop until released upon the back-stroke of the lay, because such mechanism can only act after the shuttle is lodged in its box, and must continue to act while the beat-up is being accomplished to effect its purpose of guarding against "smashes" of the warp in case the shuttle is lodged therein.

In Figs. 6 and 7 is shown a modification, in which the lever c' is made fast to the protection-rod b^4 , which is attached by bearings, in which it turns, to the lay-beam in the usual way, the lever projecting upward past the shuttle-box and impinging against the cam d^2 , which is inverted, on the arm d' . The fingers c^2 are made fast to the same protection-rod and press upon the shuttle-binders as before. The arm d' is elastic and at the end fast to the loom-frame is attached by the stud d^9 .

Fig. 5 shows a modification of the cam d^2 and elastic arm d' , the cam being made in two parts d^6 d^6 , joined to the arm, made in two parts d^7 d^7 . It will be seen that with this construction when the lever c' in moving one way strikes the outer face of the cam first it only has to overcome the tension of one of the parts of the elastic arm d' until it reaches the other part of the cam, when it must suddenly overcome the other part also, thus doubling the resistance at that point to the further expansion of the shuttle-binder, and bringing the shuttle to rest after it has been partly checked by the first portion of the cam. The form of spring arm and cam here shown is to be used in place of the one shown in Figs. 6 and 7. It is secured to the frame by screw-bolts n n and set-screws n' n' , passing through a flange a^2 of the frame. By loosening and tightening the screw-bolts n n alternately and setting up the set-screws n' n' the cam may be adjusted higher or lower in the path of the lever c' .

What we claim as new and of our invention is—

1. The combination of the vibrating lay-beam B, the shuttle-box S, mounted thereon, having one side formed of the movable shuttle-binder s, the lever c' and finger c², pivoted to the lay-beam and adapted to be alternately pressed against and withdrawn from the shuttle-binder, and the cam d², attached to the 5 loom-frame and arranged to withdraw the lever midway of the backward movement of the lay at the moment when the shuttle is thrown from its box and to press the same against the shuttle-binder midway of the forward 10 movement of the lay at the moment when the shuttle enters its box, and to allow the lever to ride over it, substantially as described.

2. The combination of the vibrating lay-beam B, the shuttle-box S, mounted thereon, 15 having one side formed of the movable shuttle-binder s, the lever c' and finger c², pivoted to the lay-beam and adapted to be pressed against the shuttle-binder, and the cam d², attached to the loom-frame and located at 20 that point in the forward path of the lever and lay-beam at which the shuttle is entering its box and is moving into the same, and arranged to nip and check the shuttle in its box while so entering by its impingement against 25 the lower end of said lever, and to allow the latter thereafter to ride over it, substantially as described.

3. The combination of the vibrating lay-beam B, the shuttle-box S, mounted thereon, 30 having one side formed of the movable shuttle-binder s, the lever c' and finger c², pivoted to the lay-beam and adapted to be pressed against the shuttle-binder, and the cam d², attached upon an elastic arm to the loom- 35 frame at that point in the forward path of the lever and lay-beam at which the shuttle is entering its box and is moving into the same,

and arranged to nip and check the shuttle in its box while so entering by its impingement against the lower end of said lever, and to allow the latter thereafter to ride over it, substantially as described.

4. The combination of the vibrating lay-beam B, the shuttle-box S, mounted thereon, 45 having one side formed of the movable shuttle-binder s, the lever c' and finger c², pivoted to the lay-beam and adapted to be pressed against the shuttle-binder, and its cam d², attached to the frame, said lever and cam being adapted to impinge against each other 50 with an elastic pressure, and the lever arranged to ride over the cam, located to bring said pressure upon the shuttle-binder and nip the shuttle while entering the box, substantially as described.

5. The combination of the vibrating lay-beam B, two shuttle-boxes mounted at opposite ends thereof, having, respectively, one side formed by the movable shuttle-binder s, the oscillating rod b⁴, mounted on said lay-beam 65 and carrying finger parts c³ c², fixed thereto and arranged to be withdrawn from and to press against said binders, the lever c', fixed radially to the rod, and the cam d², attached upon the frame in the path of the end of the 70 lever and arranged to allow the latter to ride over it and release the shuttle as it leaves one shuttle-box on the back-stroke of the lay at the moment when the shuttle is thrown from its box, and to ride over it and nip the shuttle 75 at the moment when it enters into the other shuttle-box after passing through the shed, substantially as described.
